The ornamental design for a shoe outsole, as shown and described.

DESCRIPTION

FIG. 1 is a bottom plan view of a shoe outsole according to my new design;

FIG. 2 is a side elevational view of one side of a shoe outsole as shown in FIG. 1;

FIG. 3 is a side elevational view of the other side of the shoe outsole as shown in FIG. 1;

FIG. 4 is a cross section as shown in Section 4—4 of FIG. 1;

FIG. 5 is a cross section as shown in Section 5—5 of FIG. 1;

FIG. 6 is a cross section as shown in Section 6—6 of FIG. 1; and,

FIG. 7 is a cross section as shown in Section 7—7 of FIG. 1.

The broken line showing of a shoe upper is for illustrative purposes only and forms no part of the claimed design.

FIG. 1

FIG. 3

FIG. 4

FIG. 6

FIG. 5

FIG. 7
